UNITED STATES PATENT OFFICE.

CLINTON BATEHOLTS, OF HOOSICK FALLS, NEW YORK.

DESIGN FOR A PORTABLE CABINET.

Application filed August 27, 1926. Serial No. 18,887. Term of patent 14 years.

To all whom it may concern:

Be it known that I, CLINTON BATEHOLTS, a citizen of the United States, residing at Hoosick Falls, in the county of Rensselaer and State of New York, have invented a new, original, and ornamental Design for Portable Cabinets, of which the following is a specification, reference being had to the accompanying drawing, forming part thereof.

The figure is a perspective view of a portable cabinet, showing my new design.

I claim:

The ornamental design for a portable cabinet, as shown.

CLINTON BATEHOLTS.
